[57] CLAIM

The ornamental design for a combined camera and electronic flash unit, substantially as shown and described.

DESCRIPTION

FIG. 1 is a right front perspective view of a combined camera and electronic flash unit showing our new design in an operative condition;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front elevational view thereof in an inoperative condition;

FIG. 9 is a rear elevational view thereof;

FIG. 10 is a top plan view thereof;

FIG. 11 is a bottom plan view thereof;

FIG. 12 is a left side elevational view thereof;

FIG. 13 is a right side elevational view thereof.
